UNITED STATES PATENT OFFICE.

GEORGE A. KOHOUT, OF CHICAGO, ILLINOIS, ASSIGNOR TO SHEAR-KLEAN GRATE COMPANY, OF CHICAGO, ILLINOIS, A CORPORATION OF ILLINOIS.

FURNACE-GRATE.

1,310,162.

Specification of Letters Patent.

Patented July 15, 1919.

Original application filed October 21, 1914, Serial No. 867,810. Divided and this application filed July 2, 1917. Serial No. 178,066.

To all whom it may concern:

Be it known that I, GEORGE A. KOHOUT, a citizen of the United States, residing at Chicago, in the county of Cook and State of Illinois, have invented a certain new and useful Improvement in Furnace-Grates, of which the following is a full, clear, concise, and exact description, reference being had to the accompanying drawings, forming a part of this specification.

My invention relates to furnace grates and has for its object the provision of an improved grate mounting which makes it possible to provide proper and ample bearings for tilttable grate bars, these bearings being of such construction that they coöperate with the grate bars when shaking the fire, and are so constructed that they are readily removable so that the parts which are most likely to become worn and unserviceable can be readily replaced.

In general, my invention contemplates having suitable side frames about the fire box, which side frames have provision to receive removable bearing elements interlocking with the side frames. The structure thus outlined also makes it very convenient to replace grate bars should such be found necessary.

30 This application is a division of my prior application Serial No. 867,810, filed October 21, 1914.

I will explain my invention more in detail by referring to the accompanying drawing 35 illustrating the same, in which:

Figure 1 is a top view of a portion of a grate showing my improved trunnion and bearing construction;

Fig. 2 is an end view thereof;

Fig. 3 is a perspective view of the bearing;

Fig. 4 is a sectional view on line 4—4 of Fig. 2;

Fig. 5 is a sectional view along line 5—5 of Fig. 1 showing the means for tilting the grate bars, and

Fig. 6 is a sectional view on line 6—6 of Fig. 2.

My improved structure as set forth includes a plurality of grate bars 10 each being provided at their extremities with trunnions or shafts 11. The furnace proper is provided with side frames 12 which are adapted to receive bearing elements 13, these

bearing elements accommodating the shaft 55 11. A complete bearing is shown in perspective in Fig. 3. The bearings 13 and side frames 12 are arranged so that the bearings may be slid properly into their position and be readily removable and replaceable. The 60 particular means herein illustrated to accomplish this result consist of the flanges 14, 15 provided on these bearing elements, which flanges coöperate with the side frame webs 16. These webs at their opposite extremities fit into the grooves between the flanges 14 and 15, thus to hold the bearing elements rigidly in place. The bearing elements then seat upon the shelf portion 17 provided in the side frame 12. This shows 70 that the bearings can be readily removed by merely being lifted out of their position and new ones introduced. Not only can the bearings be thus very readily replaced and removed, but new grate bars can be with 75 equal facility inserted and old ones removed.

In Fig. 4 I show a sectional view of the bearing element illustrating the flaring surface into which the shaft 11 projects. In this manner binding between the parts 11 80 and 13 is obviated. As there is a space between the grate 10 and the bearing element 13 as is more clearly evident from Fig. 4, these grate bars may be given a sidewise motion as illustrated in my prior Patent No. 85 1,196,246 issued August 29, 1916. The bearing elements 13 are provided with fingers 19 projecting inwardly, which fingers coöperate with the fingers 20 forming part of the grate bars 10. The fingers 19 are provided 90 with grooves 21 to assist in preventing formation of clinkers.

In Fig. 5 I show the grate bars 10 as provided with downwardly extending fingers 21^a which in association with the rod 22 operated from without the furnace permit of tilting the grate bars in the course of their use. It will be seen that the fingers 19 do not extend inwardly as far as the bearing element 13. There is thus an ample provision of projecting points to permit of properly dislodging those parts of the fuel which should be dislodged when the grates are tilted.

From what has been thus described the 105 nature of my invention will be readily clear to those skilled in the art. Having however thus described one form which my invention

may take, what I claim as new and desire to secure by Letters Patent is:

1. A furnace structure having side frames and tilttable grate bars, each of said grate bars having projecting shafts at its sides, bearing elements for said shafts, and means whereby said bearing elements may be removably mounted in said side frames, said bearing elements having inwardly projecting fingers for coöperating with said grate bars.
2. A furnace structure having side frames and tilttable grate bars, each of said grate bars having projecting shafts at its sides, bearing elements for said shafts, and means whereby said bearing elements may be removably mounted in said side frames, said means including dove-tailing elements, said bearing elements having inwardly projecting fingers for coöperating with said grate bars.
3. A furnace structure having side frames and tilttable grate bars, each of said grate bars having projecting shafts at its sides, bearing elements for said shafts, and means whereby said bearing elements may be removably mounted in said side frames, said bearing elements having inwardly projecting fingers for coöperating with said grate bars, said fingers having grooves in their upper faces.
4. A furnace structure having side frames and tilttable grate bars, each of said grate bars having projecting shafts at its sides, bearing elements for said shafts, and means whereby said bearing elements may be removably mounted in said side frames, said

means including dove-tailing elements, said bearing elements having inwardly projecting fingers for coöperating with said grate bars, 40 said fingers having grooves in their upper faces.

5. A furnace structure having side frames and tilttable grate bars, each of said bars having projecting shafts at its sides, bearing 45 elements for said shafts, and means whereby said bearing elements may be removably mounted in said side frames, said means including recesses along the opposite extremities of said bearing elements, said bearing elements having inwardly projecting grate fingers for coöperating with the said grate bars and said fingers having grooves in their upper faces.

6. A furnace structure having side frames and tilttable grate bars, each of said bars having projecting shafts at its sides, bearing elements for said shafts, and means whereby said bearing elements may be removably mounted in said side frames, said means including recesses along the opposite extremities of said bearing elements, said bearing elements having inwardly projecting grate fingers for coöperating with the said grate bars and said fingers having grooves in their 65 upper faces, and said bearing elements having flaring openings therethrough to accommodate said shafts.

In witness whereof, I hereunto subscribe my name this 20th day of June, A. D., 1917. 70

GEORGE A. KOHOUT.

Witness:

HAZEL A. JONES.
